UNITED STATES PATENT OFFICE.

KARL MULLER, OF SCHLIEREN, SWITZERLAND.

VESSEL FOR INFLAMMABLE LIQUIDS.

1,171,800.

Specification of Letters Patent. Patented Feb. 15, 1916.

Application filed April 17, 1913. Serial No. 761,722.

To all whom it may concern:

Be it known that I, KARL MÜLLER, a citizen of the Republic of Switzerland, residing at Schlieren, Switzerland, have invented 5 new and useful Improvements in Vessels for Inflammable Liquids; and I do hereby declare the following to be a full, clear, and exact description of the invention, such as will enable others skilled in the art to which 10 it appertains to make and use the same, reference being had to the accompanying drawings, and to letters or figures of reference marked thereon, which form a part of this specification.

15 The present invention relates to improvements in vessels for storing inflammable liquids which are lighter than water.

The improved vessel is provided with inlet and outlet valves for the liquid to be 20 stored, which when the said liquid is at rest are not exposed to the pressure of the contents of the vessel, while the inlet valve is closed automatically on the maximum volume of storage liquid being reached, and 25 the outlet valve closed automatically on completion of discharge of inflammable liquid, the construction being also such that none of the sealing liquid is lost during filling and discharging.

30 Two embodiments of the invention are illustrated in the accompanying drawing, Figure 1 being a vertical section through the first form of construction, and Fig. 2 a similar view through the second constructional 35 form. Fig. 3 is a side elevation of the pump and discharge valve employed in the modification depicted in Fig. 2.

Referring more particularly to the apparatus illustrated in Fig. 1, 1 is a cylindrical 40 reservoir open at the top and containing water or other so-called neutral sealing liquid. Near the bottom of this reservoir there is rigidly secured an inverted container or tank 2, open below. At the top 3 of this 45 tank two flexible pipes 4, 5, communicate with its interior. The first of these pipes is furnished near the top of the reservoir 1 with a stationary valve 6, to the plug of which there is connected a double armed 50 weighted lever 7, 8. To the inside wall of the reservoir 1 there is secured a substantially horizontal flat spring 9, by means of which the cock-plug can be held in open position, the lever arm 7 being engaged by the 55 spring, while the loaded arm 8 projects up-

wardly, as shown by broken lines. On a bracket (not shown) extending from the wall of the reservoir near the spring 9 there is mounted a lever 10, having a lug 11, which on ascent of the lever arm depresses 60 the spring 9.

1^x is a stop for the lever arm 7, secured to the reservoir wall. The lever 10 projects into the path of motion of a pin 13 projecting from a float 12 adapted to float only in 65 water and not in the inflammable liquid. The float 12 is guided in its movements by a stem 12^b which slides through a sleeve 1^b fixed to the top of the receptacle 1 and on said float there is secured a funnel 14 connected with a flexible pipe 15, which conducts through the wall of the reservoir 1 at 16. The pipe 5 projects through the side of the reservoir 1 substantially in the plane of the top of tank 2 and has on its free end an 70 automatically closing valve 17, which is 75 slideable on a vertical rod 18 and is suspended by means of a chain or like flexible member 19, passing over a pulley 20 and carrying a weight 21. This weight is heavier than the 80 valve 17 together with the pipe 5, so that it tends always to retain the slideable valve 17 in its highest position on the rod 18.

The operation of this apparatus is as follows: The reservoir 1 is filled with water or 85 other sealing liquid at least up to the level *a*, so that the tank 2 is always well covered. Hereupon the weighted lever 7, 8, is adjusted in the broken line position, access being had thereto through the open top of the reservoir, so that the valve 6 is open, and the spring 9, now pressing against the arm 7, 90 maintains the valve in this position. The petroleum, benzin, or other inflammable liquid to be stored, now flows through the 95 pipe 4 into the tank 2 and expels the sealing liquid contained therein, so that the latter rises in the reservoir 1, until finally the pin 13 of the float strikes the lever 10. The proportion between the volumes of storage 100 liquid and sealing liquid is such that when the level of the latter has risen in the reservoir 1 to that height at which the pin 13 strikes the lever 10, the storage liquid in the tank 2 has so far expelled the sealing liquid 105 therefrom that the latter has descended to the level indicated by the line *b*. The pin 13 now lifts the lever 10, whereupon the lug 11 depresses the spring 9. This causes release of the weighted lever 7, 8, which turns 110

into the full-line position, the valve 6 being thus closed and the flow of inflammable liquid therefore cut off.

Should, in the course of filling the tank 2 with liquid, the sealing liquid rise higher in the reservoir 1 than the float 12 can ascend, the superfluous liquid will run off through the funnel 14 and pipe 15.

To discharge inflammable liquid from the tank 2, the valve 17 must be pulled down the rod 18 and opened, so that owing to the pressure of sealing liquid in the reservoir 1 storage liquid is forced out of the tank 2 through the pipe 5 and valve 17. When the discharging operation is finished, the valve 17 must be released and will be drawn up to the top of the rod 18 automatically by the weight 21, so that it is again located above the level of the sealing liquid in the reservoir 1. Thus normally the valve 17 is not subject to the pressure of the storage liquid in the tank 2; neither is the valve 6 subject to any such pressure.

Since the storage tank 2 is completely surrounded by the neutral sealing liquid, it is impossible for air to obtain access to its interior, which is of great advantage in the case of readily inflammable liquids, such as petroleum, benzin, etc. Whatever the alteration in the volume of the storage liquid in the tank 2, the volume of the sealing liquid in the reservoir 1 always remains the same, it being only its level in the reservoir which alters though such level, even when the tank 2 is empty, is always well above the cover 3 of the tank. It will be seen that the storage liquid in the tank is constantly forced against the cover 3 of the same, so that there is never any space within which gas can form.

To indicate the quantity of inflammable liquid in tank 2, the stem 12^b carries a pointer 12^c which travels over a scale 1^c marked on the sleeve 1^b.

In the construction shown in Figs. 2-3, the reservoir 1 and tank 2 are replaced by similar receptacles 1^a, 2^a. Instead of the float 12 with attached funnel-pipe 14, 15 a float 12^a is provided within the tank 2^a, whose cover 3^a is adapted to accommodate the float in its highest position. This float 12^a immersed partly in the inflammable liquid and partly in water is also adapted to float only in water and not in the inflammable liquid. The place of the movable funnel-pipe is taken by a funnel-pipe 14^a stationarily attached to the wall of the reservoir 1^a. The flexible pipes 4, 5, conducting the valves 6, 17, are replaced by rigid pipes 4^a, 5^a, which conduct to an inlet valve 6^a and an outlet valve 17^a respectively. In the pipe 5^a there is connected a pump 22, so that the inflammable liquid can be withdrawn from the tank 2 by working the pump handle 23. The valve 17^a, controlling the pipe 5^a, is

provided with a double-armed lever 24, 25, the arm 25 being weighted, while the arm 24 bears against a segment 26 rigidly mounted on the axis of the pump 22. When the handle 23 is in the position of rest, the arm 24 bears against the end of the segment 26, the valve 17^a being closed (full-line position Fig. 3). If, however, the handle 23 is moved toward its other end position, the arm 24 is turned upward and will rest upon the periphery of the segment 26, the valve 17^a being then opened. In pumping, the handle 23 is moved to and fro between the two broken lines 27 (Fig. 3) and the arm 24 will thus remain on the segment 26, so that so long as pumping continues the valve 17^a is always open. When the handle 23 is returned to its initial position (as shown in Fig. 3) the loaded arm 25 will drop and close the valve.

In order that the float 12^a may indicate the quantity of inflammable liquid in the tank 2^a, the float is attached by a flexible member 29, passing over pulleys 30, with a weight 31, which latter is provided with a pointer 31^c adapted to travel over a scale 32. The arm 7^a of the lever 7^a, 8^a, which controls the valve 6^a, engages with a projection 28' of a double-armed lever 28, fulcrumed at 28^b to a frame-bar 1^b. When the parts 7^a, 28', engage, the valve 6^a occupies the open position and the lever 28 projects into the path of a stop 33 on the flexible member 29. When the tank 2^a is filled with the inflammable liquid, the stop 33 will tip the lever 28, whereby the parts 28', 7^a, are disengaged and the valve 6^a will be closed. 35 is a finger on the float 12^a and 34 is a valve in the pipe 5^a. This valve 34 will be closed by the finger 35, when the tank 2^a is empty of the inflammable liquid.

I claim:

1. In a vessel for inflammable liquids, a reservoir for a neutral sealing liquid, a tank for an inflammable liquid arranged inside said reservoir and permanently covered by the content of the latter, said tank being closed at the top and open at the bottom and permanently filled with liquid, independent feed and discharge means for the inflammable liquid communicating with the interior of said tank, an automatically closing valve in each of said feed and discharge means and normally situated above the level of the sealing liquid, a float adapted to float on the sealing liquid, and means acted upon by said float for releasing the feed valve when the sealing liquid has reached its upper level during filling of the vessel and exerting no control on said valve during the withdrawal of inflammable liquid.

2. In a vessel for inflammable liquids, a reservoir for a neutral sealing liquid open at the top, a tank for an inflammable liquid arranged inside said reservoir and perma-

- nently covered by the content of the latter, said tank being closed at the top and open at the bottom, and permanently filled with liquid, independent feed and discharge pipes 5 for the inflammable liquid communicating with the interior of said tank, a valve in each of said pipes and situated above the level of the sealing liquid, a float adapted to float on the sealing liquid, a lever pivotally mounted on the wall of the reservoir 10 and arranged to be acted upon by the float for controlling said feed valve, and means for vertically adjusting the position of the discharge valve.
- 15 3. In a vessel for inflammable liquids, a reservoir for a neutral sealing liquid, a tank for an inflammable liquid arranged inside said reservoir and permanently covered by the contact of the latter, said tank being 20 closed at the top and open at the bottom, a feed pipe for the inflammable liquid passing
- through said reservoir and connected to the tank, a flexible discharge pipe connected to the cover of said tank, an automatically closing valve outside the vessel on the outer 25 end of said discharge pipe, a vertical rod on which said closing valve is slidably mounted, a valve in said feed pipe, a double armed weighted lever connected to the feed valve, a float adapted to float only in the sealing 30 liquid, a lever pivotally mounted in the wall of the reservoir and arranged to be acted upon by the float when said tank is filled with inflammable liquid to close the feed valve. 35

In testimony that I claim the foregoing as my invention, I have signed my name in presence of two subscribing witnesses.

KARL MÜLLER.
